CLAIM

The ornamental design for a "pre-rolled cigarette case," as shown and described.

DESCRIPTION

FIG. 1 is a perspective view of the pre-rolled cigarette case in a closed configuration;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a back view thereof; and,

FIG. 8 is a perspective view of the pre-rolled cigarette case in an open configuration.

Broken lines depict portions of the pre-roll case and form no part of the claimed design.
